UNITED STATES PATENT OFFICE.

HOWARD C. BRUBACKER, OF SAULT STE. MARIE, ONTARIO, CANADA.

LIFE-SAVING DEVICE.

1,133,924.

Specification of Letters Patent. Patented Mar. 30, 1915.

Application filed October 9, 1914. Serial No. 865,903.

To all whom it may concern:

Be it known that I, HOWARD C. BRUBACKER, a subject of the King of Great Britain, residing at Sault Ste. Marie, in the Province of Ontario, Dominion of Canada, have invented certain new and useful Improvements in Life-Saving Devices; and I do hereby declare the following to be a full, clear, and exact description of the invention, such as will enable others skilled in the art to which it appertains to make and use the same.

My invention relates to improvements in life saving devices and more particularly to that type of devices that may be worn as garments and are particularly designed for aviators, said garment being arranged in the form of a parachute whereby an aviator or the like in case of an accident may have a safe descent.

Another object of importance is to provide a device of the character described that is formed in the nature of suit or garment to be worn by aviators and the like and is provided with a loosely overhanging skirt portion arranged to provide a parachute whereby a safe descent from aeroplanes, ships and buildings in case of fire may be made by persons seeking escape.

Another object is to provide a device of the character described that may be worn without annoyance, will prove comfortable, is reliable and efficient in operation and inexpensive to manufacture.

The above and additional objects are accomplished by such means as are illustrated in the accompanying drawings, described in the following specification and then more particularly pointed out as claimed.

With reference to the drawings, wherein I have illustrated the preferred embodiment of my invention as it is reduced to practice, and throughout the several views of which similar reference numerals designate corresponding parts, Figure 1 is a plan view of my improved safety device showing framework of the parachute portion, Fig. 2 is a front elevation partly broken away, Fig. 3 is a side elevation of the device as it would

appear when in extended and operative position; Fig. 4 is a fragmentary vertical sectional view taken through the device as applied to the wearer, Fig. 5 is a detail side elevation of one of the hooks for securing the stay elements, Fig. 6 is a fragmentary detail sectional view taken on the line 6—6

of Fig. 4, Fig. 7 is a fragmentary side elevation of a modified form of safety device, Fig. 8 is a top plan view of an attaching member used in connection with the modified form, Fig. 9 is an enlarged horizontal sectional view taken through the attaching member, Fig. 10 is a transverse sectional view, and Fig. 11 is a detail perspective view of the adjusting means for the stay ropes.

Referring to the drawings by characters of reference, the numeral 1 designates as an entirety a body portion of my improved safety device that is formed of some suitable flexible fabric and comprises a waist portion 2 and trousers 3 formed integral therewith. The waist and trousers are designed to fit the wearer snugly and said body portion is slit down the front and designed to be closed by buttons 4 or other suitable fastening elements. The bottoms of the trousers 3 have boot portions 5 attached thereto and may be formed of any suitable character. A band 6 is secured about the waist portion of the body and is provided with a suitable buckle 7 to effect adjustment thereof. A band 8 is arranged above the band 6 around the body and is provided with a plurality of hooks 9 attached thereto and which are for a purpose to be later more fully described. This band 9 is provided with a buckle 10 so that adjustment thereof may be had.

A circular flexible and preferably fabric apron or overhanging portion 11 provided with a central elongated opening 12 to accommodate the waist portion 2 of the body 1, is mounted upon the body so that it is disposed approximately in line with the arm-pits of the waist 2. This portion 11 normally hangs downwardly upon the body 1 as would an apron and is arranged to be extended outwardly approximately at right angles to the body to act as a parachute. This apron 11 is reinforced by radially extending strips 13 which are secured upon the inner face thereof and extend from the center opening 12 to the periphery thereof. A peripheral strip 14 is provided to strengthen the apron and a circular strip 15 provided upon the inner face thereof in spaced relation to the outer strip 14.

As a means to hold the apron 11 when in extended position so that it is disposed approximately at right angles to the body and is approximately concavo-convex in shape and serves as a parachute, I provide a plurality of inner stay elements 16 and outer

similar elements 17 which are secured at their lower ends as at 18 to the boot portions 5 of the body and at their upper ends are secured to the apron 11. The outer stays 5 17 are secured as at 19 adjacent to the periphery of the apron 11 and the inner stays are secured in line with the annular strip 15. Divergent strips 20 are secured to the stays 16 intermediate the ends thereof and 10 to the apron on opposite sides of each stay 16. It will be readily seen that the apron 11 is limited in its upward movement and derangement of the device is prevented.

A preferably isinglass or other transparent strip 21 is mounted in the apron 11 immediately in front of the waist 2 so that the wearer may see below him in flight.

It will be readily seen with reference to the foregoing description and accompanying 20 drawings that I have provided a simple, reliable and effective safety device that is particularly designed for aviators and may be worn with considerable comfort. In case of an accident, an aviator equipped with 25 my improved safety device may make a safe descent from the aeroplane. The apron 11 will readily open upon the dropping of the wearer and in being positioned under the arms or sleeves of the waist 2 may be held 30 in proper position in combination with the stay elements 16 and 17. The hooks 9 carried by the upper belt 8 are arranged to receive the stay elements 16 and 17 when the apron is in down position as shown in Fig. 35 4 so that entanglement thereof with parts of the aeroplane is obviated.

Referring to Figs. 7, 8, 9, 10 and 11 wherein in the modified form of my invention is 40 illustrated and the device is adapted for use without the employment of a special suit as in the preferred form, the numeral 22 designates as an entirety, the umbrella like body portion of the modified form which is similar to the body portion of the preferred 45 form but instead of being operatively connected with a garment, it is provided with a central aperture about which is placed an adjusting belt 23 provided with a buckle 24. The belt 23 is secured about the periphery 50 of the opening in the body portion 22 and provides means for the ready attachment of the device upon the wearer. A plurality of stay wires or like elements 25 are connected 55 with the body portion or apron 22 in a manner similar to that of the wires or stays 16 and 17.

Mounted upon the stay wires 25 are adjusting frogs 26 similar to those used in connection with tent stay ropes and which provide a loop 27 at the lower end of each stay 60 element.

As a means for attaching the stay element 25 to the pedal extremities of the wire, I provide attaching means designated 28 as 65 an entirety which consists of approximately

an L-shaped foot member 29. An instep strap 30 is secured to the member 29 and is provided with an adjusting buckle 31. This strap 30 is designed to pass over the foot about the instep thereof. Secured by suitable fastening elements to the upper end of the vertical portion of the L-shaped member 29 is attaching band designated 32 as an entirety. The band 32 comprises a pair of arcuate metallic members 33 and 34 that are 70 hinged to one another as at 35. The free ends of the members 33 and 34 are designed to be locked with one another by locking means which will be later more fully described. Mounted upon the free end of the member 33 is an arcuate tubular member 36 that is provided intermediate its ends and upon its outer side with an opening 37. The member 36 is approximately rectangular in cross section and is designed to abut 80 the free end of the member 34. Carried by the arcuate member 34 is a spring catch 38 provided with an enlarged head 39 on its free end. In the outer end of the head 39 a notch 40 is formed to receive one edge of 85 the opening 37. The spring catch 38 is secured by suitable fastening elements 39 to the member 34. It will be readily seen that when the member 38 is inserted into the tube 36, the head 39 will spring into position into 90 the opening 37 and receive the tube 36 at one edge of the opening in the slot or notch 40 in said head. By forcing the head 39 inwardly the catch 38 may be removed from 95 locking engagement with the tube 36. 100 hands of the workmen or others handling

The member 32 is provided at spaced points with grooved rings 41 that are mounted thereon and which are designed to receive the loops 27 so as to hold the stay elements 105 25 upon the attaching ring or member 32.

With reference to the foregoing description of the accompanying drawings, it will be readily seen that I have provided a modified form of life saving device which may be readily and easily attached upon the wearer without necessitating the employment of a special garment or shoes as in the preferred form.

In practice, I have found that the form of my invention, illustrated in the drawings, and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:—

1. A life saving device consisting of a garment arranged to closely fit the body of 130

- the wearer and a flexible overhanging and relatively wide circular band secured to the body portion at a point adjacent to the upper end thereof and beneath the arms of the wearer and flexible elements secured to the lower end of the body portion and to the periphery of the overhanging band to limit the upward movement of the band.
2. A safety device consisting of a body portion comprising trousers and waist joined integrally, a flexible circular overhanging portion secured adjacent to the upper end of the waist so as to be disposed beneath the armpits of the wearer and flexible elements secured to the overhanging portion and lower ends of the trousers.
3. A safety device consisting of a body portion comprising trousers and waist joined integrally, a flexible circular overhanging portion secured adjacent to the upper end of the waist so as to be disposed beneath the armpits of the wearer, flexible elements secured to the overhanging portion and lower ends of the trousers, and said
- 5
- 10
- 15

overhanging portion being transparent at a 25 point in front of the wearer and intermediate its inner and outer edges.

4. A life saving device consisting of a body portion formed in the nature of trousers and coat to closely fit the body of the 30 wearer, a flexible overhanging portion of circular form secured about the upper edge of the body portion and arranged to be moved outwardly approximately at right angles thereto to provide a parachute, a 35 transparent strip mounted within the front of said flexible overhanging portion at a point in front thereof to enable the wearer to see beneath him and means securing the overhanging portion to the lower portion of 40 the body portion to limit the upward movement thereof.

In testimony whereof I affix my signature in presence of two witnesses.

HOWARD C. BRUBACKER.
